(57) **CLAIM**

We claim the ornamental design for a height adjustable workstation, as shown and described.

DESCRIPTION

FIG. 1 is a perspective view of a height adjustable workstation in a raised position.

FIG. 2 is front view of the height adjustable workstation of FIG. 1 in the raised position.

FIG. 3 is a rear view of the height adjustable workstation of FIG. 1 in the raised position.

FIG. 4 is a left side view of the height adjustable workstation of FIG. 1 in the raised position.

FIG. 5 is a right side view of the height adjustable workstation of FIG. 1 in the raised position.

FIG. 6 is a top view of the height adjustable workstation of FIG. 1 in the raised position.

FIG. 7 is a bottom view of the height adjustable workstation of FIG. 1 in the raised position.

FIG. 8 is a perspective view of the height adjustable workstation of FIG. 1 in a lowered position.

FIG. 9 is front view of the height adjustable workstation of FIG. 1 in the lowered position.

FIG. 10 is a rear view of the height adjustable workstation of FIG. 1 in the lowered position.

FIG. 11 is a left side view of the height adjustable workstation of FIG. 1 in the lowered position.

FIG. 12 is a right side view of the height adjustable workstation of FIG. 1 in the lowered position.

FIG. 13 is a top view of the height adjustable workstation of FIG. 1 in the lowered position; and,

FIG. 14 is a bottom view of the height adjustable workstation of FIG. 1 in the lowered position.

Portions of the height adjustable workstation shown in broken lines form no part of the claimed design.

1 Claim, 14 Drawing Sheets
